PUNCH DEVICE

Loren H. Semler, Chicago, and Curt E. Nyberg, Skokie, Ill., assignors to Metal Specialties Manufacturing Co., Chicago, Ill., a corporation of Illinois

Filed Aug. 18, 1958, Ser. No. 755,719

4 Claims. (Cl. 30—363)

This invention relates to a punch device, and more particularly to a punch device of the plier type in which a pair of members each providing a jaw and a handle are pivotally connected together at an intermediate point.

In the usual punch structure in which the handle and jaw portions are formed of metal, the two members being connected at a central engaging point by a pivot pin, it is found that under heavy punching operations, where a large number of sheets are being perforated, the metal parts tend to become deformed slightly and to retain their set in the deformed position. A slight misalignment makes the punching operation difficult, causes excessive wear of the die and punch parts, and often makes the structure unserviceable. Because of the difficulty in operating the "sprung" punch, the punch is often discarded.

We have discovered that a highly effective punch device can be produced through the use of resilient plastic material property which will permit slight yielding of the jaw portions in the punching operation even when the load is very heavy as when a large number of sheets are being punched, and then will restore the punch parts to their original shape after the punching action. Further, the resilient character of the jaws, etc., is effective in better alignment and cutting action, and with such structure a one-piece stripper and die member can be effectively employed and a cap receptacle frictionally held for receiving the punched segments or caps. We have further found that in a plier type punch better action is obtained by disposing the pivot pin off center and more nearly in horizontal alignment with one of the jaws.

An object of the present invention is to provide the structure described above and bring about the new results and advantages referred to. Another object is to provide in a punch device resilient members which permit high pressures to be employed in the cutting of a plurality of paper plies while at the same time immediately restoring the parts to their original shape and position after the release of pressure. A still further object is to provide yielding jaw means which support and facilitate the action of the punch member in combination with the die member. Another object is to provide in a plastic punch structure a one-piece, U-shaped stripper and die member adapted to be anchored to one of the jaws of the punch while also providing a cap receiver adapted to frictionally engage the lower portion of the plastic jaw. Yet another object is to provide sturdy means for supporting a pivot pin within engaging portions of the jaw and handle members and resilient spring and handle means for operating the jaws. Other specific objects and advantages will appear as the specification proceeds.

The invention is shown, in an illustrative embodiment, by the accompanying drawing, in which—

FIGURE 1 is a perspective view of a punch device embodying our invention; FIG. 2, an enlarged longitudinal sectional view; and FIG. 3, a perspective view of the one-piece stripper and die member.

In the illustration given, A designates a plastic member providing a handle portion 10 and a jaw portion 11; B designates a member providing a handle portion 12 and a jaw portion 13. The member B is provided near its forward portion with a circular body portion 14 adapted to receive a pivot pin 15. The portion 15 is received within a hollow portion of the member A, and the pin 15 ex-

2

tends through the two members A and B so as to pivotally connect the same in the position shown in FIGS. 1 and 2.

The jaw 13 of member B carries a punch pin or cutter pin 16 provided with a pressure plate 17 adapted to rest against the inner face of the jaw 13 and an integral retainer pin 18 extends through an opening 19 in the jaw and at its top is peened to form a retainer flange 20.

The lower jaw 11 is provided with an aperture 21 for receiving cut segments or caps, and is preferably provided at its bottom with a resilient lip 22 adapted to frictionally engage the yielding resilient flange portion 23 of a plastic cap receptacle 24. The jaw 11 is preferably recessed to receive a U-shaped metal stripper and die member 25, and pins 26 extend through openings in the lower leg of the member 25 and through the plastic jaw 11 for anchoring the member 25 in the position shown in FIG. 2. The stripper member is provided with a recess 27 adapted to receive the punch pin 16, and at its forward end with a guide member 28. If desired, the stripper may be provided with additional recesses 29 and 30, as illustrated best in FIGS. 2 and 3.

The lower leg of the member 25 is provided with a die opening 31 adapted to receive the punch pin 16 and to guide the punch pin as it travels downwardly in the cutting operation. As shown best in FIG. 1, we prefer to provide the upper jaw 13, and on each side thereof, with a scale indicated by the numeral 32, so that in the punching operation an accurate punching of holes can be made in several punching operations, the user being thus able to accurately punch successively holes in sheets which are later to be brought into alignment. By the scale located, as shown, directly above the stripper and die member 25, it is possible to punch the holes uniformly in sheets which are fed successively to the punch device.

By employing a tough resilient plastic material in the forming of the jaw and handle members, we have found that the punch device has much longer life and operates uniformly through its life and without tendency to become deformed, as has heretofore been the experience with metal punches. The plastic resin employed is preferably one of elastic type so that after the bending under high pressures during the punching action, the plastic members will rebound to their initial shape. Any suitable plastic resin having the necessary strength and having the elastic property above referred to, may be employed. For example, acrylonitrile plastic gives the necessary strength, while at the same time providing the elastic property required to restore the parts immediately to their initial shape after the release of pressure. Styrene plastic filled with fiberglass has the necessary strength and the rebound that is needed. Obviously, other plastics such as nylon, polyethylene, and a variety of plastic resins having elastic properties, may be employed. Since such resins are well known, a further detailed description herein is believed unnecessary.

We have discovered that more effective cutting action is obtained where the pivot pin 15 is below the center of the engaging members A and B. In the specific illustration given, the drop from the center is approximately .060", and it will be observed that the pin now extends below the top surface of the lower jaw 11 and in horizontal alignment with the lower jaw. With this structure, the punch pin 16 strikes the paper to be perforated at an angle and enters the die opening 31 along one side, so that the die opening itself can serve as a guide for the pin 16 in its downward travel. Since the jaws are resilient, the pin and die, when engaged, are permitted by the jaws to travel in true alignment with each other.

The handle portions 10 and 12 are preferably hollow and are provided with central reinforcing walls 33, and a compression spring 34 is effectively housed between the wall 33 and adjacent side wall of each handle member 10

and 12, as shown more clearly in FIG. 2. The handle members are also provided with transverse members 35, 36 and 37. The members 36 and 37 of each of the handle members 10 and 12 are adapted also to serve as stops so as to limit the inward movement of the plastic handle members.

Operation

In the operation of the punch device, the paper to be punched is inserted within the mouth of the stripper and die member 25 and in the desired alignment with the scale 32 thereabove and the handle members 10 and 12 are then squeezed in the usual manner. The resilient jaws 11 and 13 move uniformly in an arc and the lower portion of the punch pin 16 presses into the paper and into the die opening 31. The die and pin automatically align themselves with the jaws yielding slightly during the resulting linear cutting action. The flex in each handle maintains the relative jaw positions so that the alignment of the punch and die will be on the same arc of the circle. Even though a large number of sheets are punched and the strain upon the jaws is heavy, an effective severing operation is accomplished and immediately upon the release of pressure, the jaw and handle portions spring back to the original position. Thus, while the resilient jaws provide the necessary strength for supporting the punch and die parts, they enable the parts to telescopically engage at wider angles for more effective severing of the paper, while then yielding so that the parts are guided in telescoping relation with each other and after the severing action and when the pressure is released, there is an immediate rebound of all of the plastic parts to their original position and with no permanent deformation therein. Repeated operation may, therefore, take place and with the parts always operating in the same uniform manner.

The stripper and die member 25 reinforces the lower jaw, maintains the sheets to be severed in proper alignment with the lower jaw, and strip the paper from the punch after the cutting operation. The jaw further provides resilient flange portions 22 for gripping the resilient lip portions 23 of the receptacle 24 so that the receptacle is frictionally held tightly in place during the punching operation, but is removable for emptying the caps.

While, in the foregoing specification, we have set forth in considerable detail a description of one embodiment of the invention, it will be understood that such details of structure may be varied widely by those skilled in the art without departing from the spirit of our invention.

We claim:

1. In a punch device having opposed rigid metal punch pin and die elements and handles pivotally connected together, resilient jaws carried by said handle members and supporting said pin and die elements, said jaws being of plastic resin having elasticity whereby said jaws flex under high pressure during a punching action and completely recover their original shape upon the release of said high pressure.
2. The structure of claim 1 in which said handles are equipped with inwardly-extending stop members which limit the degree of flex of said jaws.
3. The structure of claim 1 in which said jaws and handles are formed of acrylonitrile plastic.
4. A punch, comprising a pair of longitudinally-extending members pivotally connected at an intermediate point, each of said members having a handle portion and a jaw portion and with the jaws extending in opposed relation, said jaws and handles being formed of a plastic resin having elasticity, a punch pin secured to the end portion of one jaw and extending inwardly, a metal die secured to the other jaw and adapted to receive said punch pin, a pivot pin pivotally connecting said members in offset relation from the engaging centers of said members and in general alignment with said die, said jaws being of such dimensional cross section as to cause them to flex during punching action and completely recover their original shape after the release of punching pressure, and stop means carried by said handles limiting the degree of flexing of said jaws.
